LOADER AND PACKER FOR REFUSE TRUCKS

John P. Calamore, Flushing, N. Y., assignor to
 City Tank Corporation, Corona, N. Y., a corporation of New York

Application January 18, 1951, Serial No. 206,632

12 Claims. (Cl. 214—518)

1

This invention relates to a tailgate loader and more particularly to a tailgate loader and auxiliary packer for refuse trucks.

This application is a continuation-in-part of my application Serial No. 126,496, filed November 10, 1949, now Patent No. 2,660,326, granted Nov. 24, 1953.

It is an object of this invention to provide a loader for a refuse truck in which a rotary prime mover operates an endless conveyor lift or escalator type of load shifter which moves refuse or the like from a relatively low level loading hopper along an angularly directed tailgate to direct the load well above the floor level of a refuse truck within a closed body and to continuously distribute the charge within the body with compacting force whereby interruption in loading is minimized and a high "pay load" may be filled into the refuse truck body economically.

In my prior application aforesaid I have provided in combination with a refuse truck, a loader and packer mounted on the tailgate of a closed body truck in which an endless conveyor having lift blades is arranged to move refuse from a loading hopper at a low level and deposit it well above the floor level of the refuse truck, through an opening adjacent a secondary hopper or arcuate wall in relation to which a packer plate is driven, to provide a bodily swinging movement by an eccentric cross shaft which swings the plate adjacent the secondary hopper to provide a pushing force along the surface or bottom wall of the hopper which minimizes recycling and which effects a forward and upward pushing compacting force to within the truck body, with return clearing movement leaving an opening free from obstruction and which does not churn up the refuse or tend to return the refuse to cause interference with the lifts.

I have found that long life, increased wear resistance, relative freedom from interruption of the associated parts, and higher "pay loads" may be secured by a great reduction of the scraping action against the arcuate hopper wall with greater clearance therefrom and gravitational deposition of the refuse within the truck body effecting an initial shearing and the application more directly of the compacting force of a compacting plate against the mass of refuse within the body of the truck.

Still more particularly, I have found and it is an object of this invention to provide, in combination, a refuse truck having a relatively closed body including a tailgate construction in which an endless conveyor or escalator having lifts or

2

blades continuously operating within a low level hopper, shifts the load along an inclined plate on the tailgate to a fill aperture above the truck floor level, the load being distributed and compacted within the truck body by a continuously operating packer plate which exercises a shearing action of the refuse adjacent the filling aperture and cyclically delivers to the gradually accumulated bed of gravitationally deposited refuse, a downward, forward and upward compacting action and return clearing movement which does not churn, loosen or return the load to the initial position.

Still more particularly it is an object of this invention to provide in combination with a refuse truck, a loader and compactor characterized by combining with a truck body to be loaded, an endless conveyor lift or escalator which continuously serves to shift refuse from a hopper at a low level, to deposit the load through a fill opening within the body above the floor level, and cyclically coordinating with the conveyor lifts or blades, a packer plate which is driven by an eccentric to pack the load within the truck body, to give to the refuse a downward, forward and upward movement cyclically repeated, without churning and returning the load and to afford the minimum obstruction to the incoming load, to effect a shifting and packing of the load over a great width of the truck body, downwardly and forwardly thereof, to secure high "pay loads."

Still more particularly it is an object of my invention to provide a refuse truck having substantially closed body and a tailgate loader and packer combining with a primary and relatively low level hopper, a feed therethrough comprising an escalator type of lift which moves the load along a substantial width of the truck and deposits the same through an opening in the truck above the floor level and near the roof of the truck, and which may handle a variety of refuse with little or no likelihood of stalling, and which is characterized by the facility with which it may be reversed to release jammed infrangible refuse or other material without damage to the mechanism or delay which may be involved in freeing the load, and characterized by continuously and rapidly executed cyclical operations co-ordinating a continuously moving endless chain conveyor with a packer providing a compacting force distributed over a large proportion of the width of the truck, which packer provides a combination forward and upward movement to the oncoming refuse, without churning or return of the load, and including a very simple number of

cooperating parts which assure long life and minimum maintenance service.

Still more particularly it is an object of this invention to combine with an endless conveyor lift or escalator a tailgate loader which may be powered by a rotating prime mover such as a hydraulic motor, to supply adequate power efficiently to prevent load channeling in movement to within the body and exert positive rake in effecting the shifting of the load to the interior of the body and secure long life and economy of maintenance.

To attain these objects and such further objects as may appear herein or be hereinafter pointed out, I make reference to the accompanying drawings forming a part hereof, in which—

Figure 1 is a fragmentary side elevation, partly in section, of a refuse truck and tailgate embodying my invention;

Figure 2 is a magnified perspective view of a packer plate employed by me;

Figure 3 is a magnified section of the upper portion of the tailgate, disclosing the packer plate assembly;

Figure 4 is a section taken on the line 4—4 of Figure 3;

Figure 5 is a fragmentary longitudinal section of the tailgate and packer assembly of another embodiment of my invention;

Figure 6 is an end elevation thereof;

Figures 7 to 12 are diagrammatic views showing the cycle of movement of the packer plate, with the embodiment illustrated in Figures 1, 2 and 3;

Figures 13 to 18 are diagrammatic views showing the various positions of the packer plate in accordance with the embodiment illustrated in Figure 5.

Summarizing my invention, I provide, in combination with a refuse truck body, a tailgate having a unitary assembly of an endless chain conveyor or escalator type of lift along an inclined tailgate plate running from a low level hopper across a substantial width of the truck body to a filling aperture well above the floor of the truck and adjacent the roof thereof, adjacent which point refuse is stripped or sheared from the filling opening by a transversely moving packer plate extending for a substantial width of the body of the truck, and, by an eccentric rotary drive, is given a combined pushing and tilting movement downwardly, forwardly and upwardly within the truck body without the need for shielding to prevent recycling, scattering or churning and all performed by a rotary prime mover, preferably a hydraulic motor, for continuous and uninterrupted operation whereby high "pay loads" are transported economically and with the minimum amount of wear due to abrasion in handling refuse or loss of use of the truck for repair.

Making reference to the drawing, I illustrate my invention in connection with a truck chassis 10 having a refuse body 11 mounted thereon. The truck body desirably has a closed roof 12 and by side walls which are angularly directed provides the fill opening 13, which is covered by a tailgate assembly 14. The tailgate assembly is supported in body closing position by the bracket arms 15 aligned with the suspending ears 16, and coupled thereto by the hinge pintles 17, to hingedly support the tailgate assembly on the truck body.

The bracket arms 15 are extended to provide offsets 18 supporting the knuckle 19 for engagement by the hydraulic piston 20 to power actuate the tailgate assembly into an open position when

duly unlocked by latching means (not shown). The tailgate assembly includes a closure plate 21, extending downwardly below the truck floor 22, and supports an arcuate bottom extension 23 combining with side plates 24 to form a casing through which refuse may be fed via the hopper 25 having the usual can stops and like known equipment. The side plates 24 adjacent the hopper support end guides comprising incomplete annular flanges 26 extended from a drum 27 and mounted on the side plates of the hopper and held thereto by the bolts 28, passing through slots 29 for lengthwise adjustment of the end guides. The flanges 26 are aligned with the tracks 30 and 31 leading up to each side of the main drive shaft 32, supporting the sprockets 33 for guiding the conveyor chains 34 on which are mounted the lifts or blades 35 and guide rollers 36. The drive shaft 32 supports the sprockets 33 to direct the lifts 35 to and past the fill opening or throat 37, which is outlined by the breaker edge 38 which is reinforced by the reinforcing bar 39, having extending therefrom an arcuate edge member 40 inwardly of the plate 21 whose arc or radius corresponds substantially to the path of the packer hereafter to be described. Side plates 38a may be extended from the side edges 37a to extend across the throat inwardly of the throat opening 37.

The inward face of the tailgate plate 21 has mounted thereon journaled brackets 41—41 in which are journaled the stub shafts 42—42. The stub shafts on the complementary ends support circular side plates or disks 43 and have eccentrically trunnioned adjacent the periphery of the side plates the cross bar 44. The cross bar 44 pivotally supports by suitable bearings one end of the packer plate 45, and has an overhang which projects to the periphery of the side plates and includes a reinforcement by the reinforcing channels 46 having its leading edge shielded by the shoe 47. The forward face 48 of the shoe may be angularly directed or in parallelism with the plane of the packer plate 45 in accordance with the type of refuse to be handled, to have a greater or lesser degree of positive rake. Thus I have found that the rake may be made of a greater degree of positiveness for less frangible or mushy refuse and that where more frangible refuse, such as ashes or cinders is to be handled, the positive rake may be diminished to provide a flat plate throughout, to minimize abrasion, increasing the life of the packer plate and minimize any stalling tendency, where a great amount of such refuse is to be handled.

The packer plate 45 is supported adjacent its upper edge 49 by the cross bar 50, the pivotal ends 51 whereof are coupled to the bell crank links 52, whose branches 53 thereof support therebetween the auxiliary plate 54 to extend the edge 55 thereof in close contact with the upper edge 49 of the packer plate 45. For this purpose, this latter edge may be arcuately formed to provide a contact surface to minimize the gap between the edge 55 and the edge 49. The plate 54 thus provided may have its end 56 extend to the elbow of the bell crank levers 52 previously described. The branches 57 terminate in bearings 58 and are coupled to support the assembly on pintles 59 at a fixed point extending from the bracket arm 60 spaced inwardly in relation to the axes of the countershafts 42. All these parts may be supported on the tailgate to form a unitary assembly. The countershafts 42 have sprockets 61, each of which has

chain belts 62 coupled to the sprocket wheel 63 on the main drive shaft 32. The main drive shaft 32 has a gear 64 and chain or the like drive 65 coupled to the motor 66 which may be a hydraulic motor for rotatively driving the gear 64 with adequate gear reduction to secure a predetermined mechanical advantage, it being understood that other transmission means with suitable reduction gearing may be employed to transmit the power from the motor to the drive shaft 32.

By the construction described, I find it desirable to position the number of lifts or blades 35 and adjust the gear reduction for driving the countershaft 42 that the latter in turning the side plates 43 coordinates the assembly to provide a movement of four lifts across the throat for each revolution of the side plates 43 and to coordinate the position of a lift or blade 35 that it reaches a position substantially coincident with the edge 38 when the cross bar 44 is diametrically opposite to the position of the edge 38 of the throat, it being understood that the leading edge or shoe 47 clears the arcuate surface 49 with each revolution with clearance depending upon the refuse to be handled as described. The provision of eleven lifts 35 on the conveyor distributes the wear on the members.

The endless conveyor chains 34 are driven by the driving shaft 32 to direct the lifts 35 in close wiping contact with the plate 21 between the side plates of the conveyor casing 24 to rise one flight in the direction shown by the directional arrow R. The packer plate driving shafts 42 are driven in a counter direction. The downwardly directed flight of the conveyor is separated from the upwardly directed flight adjacent the throat 38 by the partitioning breaker plate 67 which is provided at its forward end with an angular shoe 68 at a point below the edge 38. A segment comprising a deflector plate 69 is angularly directed towards the throat 37 adjacent the shaft 32 and acts as a shield as will be understood as this description proceeds.

From the installation as described, refuse may be deposited into the hopper and the refuse cans may be stacked in inverted position over the hopper and held so by resting on a sill pad and hinged can stop supplied with the hopper. When the motive power is put into operation, the refuse is carried by the lifts or blades 35 along the angular plate 21 up to the point where the debris is brought adjacent the throat 37 spilling over the edge 38 and gravitating into the space below the packer and spreading initially into the angular extension of the tailgate above the truck floor 22. With the synchronization of the flights with respect to the packer plate 45 as shown in Figure 3, an unobstructed passage is provided and permits a wide variety of refuse particles to be discharged into the hopper. Sticks, bars, cardboard or wooden cases are broken up as the lifts bring the material into contact with the leading edge of the breaker plate 67 and shoe 68. As the packer plate 45 is rotated to come adjacent the edge 38, any refuse projecting into the throat is deflected by the packer plate 45 when the packer plate assumes the position as shown in Figure 8. Any remnant of material is then subject to a tilting, shearing, chopping or breaking action as will be observed from the position of the respective parts of the lifts and packer plate in Figure 9. The progressive movement of the packer plate to the positions shown in Figures 10, 11 and 12 will thereafter

10 15 20 25 30 35 40 45 50 55 60 65 70 75

6 tend to distribute the refuse within the truck body.

While the edge 38 may be extended arcuately to provide a bottom cooperating with the rotary side plates to form a secondary hopper, as described in my prior application aforesaid, to aid in the deflection and spreading of the refuse to a greater extent to the interior of the truck body, sharp downward clearance is preferred since I have found that this greatly reduces the drag on the packer permitting the initial gravitational deposition of the refuse and the handling of infrangible material with greater facility. Upon an accumulation of debris below the packer, the oncoming refuse is thrust more deeply into the corner at the extreme end of the truck by the compacting blows of the leading edge 47 of the packer in the downward or return half movement, as the packer passes the bar 39. The accumulated mass is then projected downwardly, forwardly with positive rake pushing the load ahead of it in a direction normal to the surface of the plate as will be clear from an inspection of Figures 9 to 12. The upward first half movement to recycle the packer to the position shown in Figure 7 is accompanied by a clearance movement leaving a substantial passage which is unobstructed and in no way churning the refuse or directing it back into the conveyor through the throat 37.

The coordinated relationship of the plate 54 to the packer blade 45 further aids in shielding the conveyor from any tendency to create churned-up debris as well as to compress the heaped material which may be diverted to each side of the packer downwardly and forwardly to compact the same. The rapid cyclical movements as described progressively move the load forward of the truck after compaction below the packer for a substantial width of the truck body with a minimum amount of channeling to leave uncompacted masses, since any material which is heaped up above the packer and to the sides thereof is gradually compacted or thrown back in the path of the packer to be moved forward within the truck downwardly, forwardly and upwardly in a highly compressed condition to provide a profitable "pay load." The compacting action being carried against a more or less resilient bed, stalling of the motor is unlikely, whereby abrasion and caking tending to jam the packer is minimized, making the use of an unusually high powered motor unnecessary.

The high clearance characteristics of the throat and the space between the plates 43 provide an exceedingly simplified assembly which requires no attention should it be found necessary to reverse the operation to clean the throat and conveyor to free it from any highly infrangible object which may block the passage. Accordingly, forward and reverse movement may be effected by the operator without special attention to the condition and position of the material within the conveyor casing.

While I have shown and described a swing linkage support for the packer plate 45 as it is shifted by the eccentric of the side plates 43 in relation to the breaker bar 39 as contrasted with the arcuate extended wall of my prior application, it will be understood that the swing linkage support in combination with the breaker bar 39 of the character herein disclosed may follow the simple form of swing linkage shown in my prior application as more specifically

described and illustrated in Figures 5 and 6 and diagrammatically illustrated in Figures 13 to 18. Likewise, the combined swing linkage comprising the bar crank link support and auxiliary plate 54 may be employed with an installation in which the breaker edge 38 has extended an arcuate bottom wall forming a secondary hopper as in my prior application.

Making reference to Figures 5 and 6 comparable parts to that shown in the embodiment illustrated in Figures 1 to 4 are correspondingly numbered and all essential details identical. In this construction, however, the packer plate 45 has its edge 49 supported by links 54a whose suspending end 57a has the pivot 59a extended substantially vertically over the center of the countershafts 42 as will be more clearly shown from the diagrammatic assembly in Figures 13 to 18. The cycle of operation is substantially the same as in the prior embodiment, though to some extent sacrificing positiveness of rake forward of the truck in all positions of movement of the packer plate after progressing the movement thereof beyond the shearing position adjacent the breaker edge 38. Likewise, it will be observed that as contrasted with the embodiment illustrated in Figures 7 to 12, compaction of material which may climb adjacent the roof of the body occurs at a slightly lower level thereof, and a simplification of the installation may dictate its preference over the employment of the packer plate and auxiliary extension of the first embodiment described.

As shown particularly in Figures 1 and 5 and previously described, the closure plate supports an arcuate bottom extension 23 combining with side plates 24 to form a casing through which the refuse may be fed via the hopper 25 having the usual can stops and like known equipment. It will also be observed that the bottom extension walls form a constant clearance enclosure about the tracks 39, 41 for guiding the chains 34 so that blades 35, after reaching the nip indicated by sharp breaker edge 23(a) extending from the hopper wall 25(a) will 45 carry the refuse without change in compaction at the hopper bottom extension wall. A change in clearance beyond the sharp breaker edge overcomes the unusual load of compaction as compared with that involved in a tangential relation of the bottom wall to the path of the lifts. This feature, in addition to effecting the breaking up of refuse, avoids the need (with a great many forms of refuse) of using resilient boots, as stalling loads are largely eliminated.

It will thus be observed that I have provided a loader and packer which may be operated uninterruptedly by powering the same with a rotary prime mover which rotates and advantageously employs the momentum of such movement to drive the shaft of an endless conveyor and similarly rotate the packer plate in cooperative relationship thereto, thus having all the desirable features of an endless conveyor in that the hopper into which the endless conveyor dips to raise the load from a low level may have the latter loaded without interruption and may serve to fill the body, through a throat on the tailgate at a high level. Also by having the packer extend for a substantial width of the truck body as described, I minimize channeling of the load while compacting it and shifting it in compacted condition within the truck body, to achieve a high "pay load" economically and

with a highly simplified low-cost assembly, assuring long life and low-cost maintenance.

Having thus described my invention and illustrated its use, what I claim as new and desire to secure by Letters Patent is:

1. In a refuse truck having an angularly inclined tailgate, a loading hopper at a low level mounted thereon including, in combination, a loading and packer assembly having an endless conveyor driven by a rotary drive shaft having lifts or blades guided in a casing on said tailgate, continuously to raise material and direct it from the loading hopper at a low level, into which one flight end of the conveyor is directed, and is upwardly extended over and across a filling throat opening, over which the other flight end of the conveyor is directed, said filling opening having a breaker edge located on said tailgate above the floor level of the truck body and extending transversely for a substantial width of the truck body, a breaker bar between flights of said conveyor in opposed relation to said edge, said packer assembly comprising spaced journaled countershafts having a rotary power drive connection with said first shaft, each of said countershafts having a crank arm in contiguous spaced position and connected by a cross bar, said cross bar supporting a pivotal packer plate adjacent one end across said throat and breaker edge and a swing linkage support for said packer plate adjacent the opposite end, whereby said packer plate is directed cyclically and uninterruptedly with respect of said lifts to transmit a downward, forward and upward motion throughout the depth of the plate over said throat in one phase of movement and clearing said throat in a return phase movement.
2. In a refuse truck in accordance with claim 1 wherein said linkage support comprises a bell crank lever arm.
3. In a refuse truck in accordance with claim 1 wherein said swinging linkage support comprises a pair of bell crank levers supporting the free end of the packer plate between which an auxiliary plate is supported contiguous to the packer plate.
4. In a refuse truck in accordance with claim 1 wherein said endless conveyor directs the lifts across said throat opening, having the upwardly directed and downwardly directed flights adjacent said throat opening separated by a breaker bar adjacent said throat opening and extending across the width of said throat.
5. In a refuse truck in accordance with claim 1 wherein the conveyor directs the lifts to have one flight directed across the throat opening, the downwardly directed flight being separated by a breaker plate including a deflector, angularly directed toward the throat opening.
6. A tailgate loader and packer for a refuse truck or the like including spaced rotatable high level and low level shafts, an eccentric countershaft connected with one of the said high level rotatable shafts and driven thereby, a packer plate, the lower edge of which is pivotally mounted to said countershaft, and a swinging linkage support adjacent the opposite edge of the packer plate, said linkage comprising spaced bell crank levers, one branch of each of which levers supports the upper edge of said packer plate, the other branch of each of which levers is axially displaced vertically from said shafts.
7. A tailgate loader and packer for a refuse truck or the like including spaced rotatable shafts, an eccentric countershaft, a packer plate, the lower edge of which is pivotally mounted to

said countershaft, and a swinging linkage support adjacent the opposite edge of the packer plate, said linkage comprising spaced bell crank levers, one branch of each of which levers supports the upper edge of said packer plate, the other branch of each of which levers is axially displaced vertically from said shafts, and an auxiliary plate contiguous to said packer plate supported between said bell crank lever links.

8. In a refuse truck having an angularly inclined tailgate, a loading hopper at a low level mounted thereon including, in combination, an endless conveyor driven by a rotary drive shaft having lifts or blades guided in a casing on said tailgate, one flight of the conveyor adjacent said tailgate serving to raise the material to direct it from the loading hopper at a low level across a filling throat opening on said tailgate including a guide above the throat opening, the return flight being separated from the first flight by a breaker plate for deflecting refuse raised by said lifts into said throat opening.

9. In a refuse truck having an angularly inclined tailgate, a loading hopper at a low level mounted thereon including, in combination, an endless conveyor driven by a rotary drive shaft having lifts or blades guided in a casing on said tailgate, one flight of the conveyor adjacent said tailgate serving to raise the material to direct it from the loading hopper at a low level across a filling throat opening on said tailgate at a high level including a guide above the throat opening, the return flight being separated from said first flight by a breaker plate for deflecting refuse raised by said lifts into said throat opening, said breaker plate having a deflecting segment adjacent the upper portion of said throat opening.

10. In a refuse truck having a tail gate inclined and terminating in a loading hopper at low level into which an endless conveyor is angularly guided, with lifts or blades to raise material from said hopper to a filling throat above the floor level, the combination comprising a bottom wall in said hopper having a sharp breaker edge adjacent the leading nip point of 45

said wall and path of said flights, said wall being curved arcuately with substantially constant clearance in the trailing position with respect to the arcuately guided portion.

5 11. In a refuse truck, a truck body having a rearwardly and angularly extended tailgate wall, a tailgate loader along said tailgate wall, comprising a chain lift extending from a fill hopper below the truck body floor and guided adjacent the tailgate wall towards the roof of the truck body, the combination having a fill opening in the tailgate wall above the floor level over which fill opening the lift directs the load to deposit the load in a deposition zone gravitationally below said fill opening on the floor of said truck body, a cyclically operated packer plate assembly mounted for swinging downward, forward pushing motion and return clearing movement in timed relation to and continuously during the 15 deposition of the load by said lift.

10 12. In a refuse truck in accordance with claim 11 wherein said fill opening is extended and spaced from each side wall of the truck body and said packer plate assembly is substantially coextensive with said fill opening.
